(57) **CLAIM**

We claim the ornamental design for a rolling support for a surface-treating appliance, as shown and described.

DESCRIPTION

FIG. 1 is a front view and side perspective view of a rolling support for a surface-treating appliance according to this invention

FIG. 2 is a front view of a rolling support of the design according to this invention.

FIG. 3 is a rear view of a rolling support of the design according to this invention.

FIG. 4 is a view from one side of a rolling support of the design according to this invention.

FIG. 5 is a view from the other side as shown in FIG. 4 of a rolling support of the design according to this invention.

FIG. 6 is a plan view of a rolling support of the design according to this invention; and,

FIG. 7 is an underneath view of a rolling support of the design according to this invention.
